(57) **CLAIM**

The ornamental design for a folding bowl with lid, as shown and described.

DESCRIPTION

FIG. 1 is a top side plan view of a folding bowl in an unfolded flat position with dashed lines representing creases; FIG. 2 is a top side plan view of a folding bowl lid in an unfolded flat position with dashed lines representing creases; FIG. 3 is a perspective view of the folding bowl folded into the form of a bowl;

FIG. 4 is a bottom side plan view thereof folded into the form of a bowl;

FIG. 5 is a top side plan view thereof folded into the form of a bowl;

FIG. 6 is a right side plan view thereof which is symmetrical with a left side plan view;

FIG. 7 is a front side plan view thereof which is symmetrical with a rear side plan view;

FIG. 8 is a perspective view of the folding bowl folded into the form of a bowl with the folding bowl lid folded and secured onto the bowl;

FIG. 9 is a bottom side plan view thereof;

FIG. 10 is a top side plan view thereof;

FIG. 11 is a right side plan view thereof which is symmetrical with a left side plan view; and,

FIG. 12 is a front side plan view thereof which is symmetrical with a rear side plan view.

The folding bowl and folding lid have been shown separately in FIGS. 1-7 for clarity of illustration only.
